UNITED STATES PATENT OFFICE

CHRISTIAN BODMER, OF NEW BRITAIN, CONNECTICUT, ASSIGNOR TO THE STANLEY WORKS, OF NEW BRITAIN, CONNECTICUT, A CORPORATION OF CONNECTICUT

BENCH VISE

Application filed December 17, 1927. Serial No. 240,808.

This invention relates to a vise of the type adapted to be clamped to a bench or the like and has as its aim to provide a device of this sort which has various features of novelty and advantage.

More particularly an aim of the invention is to provide an improved vise which is characterized by its extreme simplicity in construction, by its strength and durability, and by its convenience and effectiveness in use.

My improved vise comprises a relatively few parts, each of which while being relatively cheap in manufacture, is strong enough to stand considerable abuse. The parts are so arranged and assembled that the vise may be readily secured to a bench and articles or pieces of work of various kinds may be easily and quickly clamped in the vise, and when so clamped, are securely held in place.

Other objects will be in part obvious and in part pointed out more in detail hereinafter.

The invention accordingly consists in the features of construction, combination of elements and arrangement of parts which will be exemplified in the construction hereinafter set forth and the scope of the application of which will be indicated in the appended claims.

In the accompanying drawings wherein I have shown for illustrative purposes one embodiment which the present invention may take:

Figure 1 is a perspective view;

Fig. 2 is a forward end view thereof;

Fig. 3 is a side view;

Fig. 4 is a top plan view; and

Fig. 5 is a sectional view taken substantially on line 5—5 of Fig. 4.

Referring to the drawings in detail, my improved vise includes a fixed jaw element and a movable jaw element, the fixed jaw element having means for clamping the same

to a bench or other support, and the movable jaw element having a screw operating in a nut carried by the fixed element so that the jaws may be moved relatively to one another.

The movable jaw element is preferably in the form of an integral casting having a longitudinally extending bar or slide 10 and a jaw 11 adjacent one end of the slide and extending transversely or at right angles thereto. The jaw 11 is in the form of an upstanding web or flange, and extending forwardly from the bottom web is a base flange 9. Between the flanges 9 and 11 is a reinforcing rib or web 12. The flanges 9 and 11 in effect constitute an angle bar. The bar or slide 10 is preferably channel-shaped, thus providing the bar with an upper web 13, a lower web 14 and a rear wall 15 which is preferably longitudinally slotted as at 15'. The channel-shaped bar 10 has a forward end wall 16 in which is journalled a screw 17 having on its outer end an operating handle 18. Pinned to the screw 17 just rearwardly of the end wall 16 is a collar 19 for preventing endwise movement of the screw relative to the bar. The rear end of the screw has a gudgeon 20 which is rotatably mounted in a lug or ear 21 carried by the bar 10 adjacent its rear end and extending into the channel, as illustrated most clearly in Fig. 1.

The fixed jaw element has an angle bar formed of an upstanding web or flange 30 opposed to the flange 11 and a base flange 31 horizontally disposed and extending rearwardly from the lower end of the flange 30. Between the flanges 30 and 31 is a reinforcing web 32. Depending from the base flange 31 is an L-shaped arm 33 which terminates in a boss 34. The L-shaped arm, together with the bottom of the base flange 31, forms an open guide-way or channel in which is slidably mounted the bar 10. Extending from the vertical leg of the arm 33 is an integral lug 35 which has a threaded bore or

aperture 36 through which extends in threaded engagement the screw 17. The boss or projection 35 extends into the channel of the bar 10 and the slot 15' accommodates the inner end of this projection.

5 The means for clamping the vise to a support such for instance as a wood-worker's bench, comprises a screw 40 threaded in the boss 34 and having swiveled to its upper end 10 the head 41. It will be noted that this head is opposed to the base flange 31 so that the support designated by the letter S may be 15 clamped between this flange and the head 41. The screw 40 may be turned by a handle 42.

15 From the foregoing description taken in connection with the accompanying drawings, it will be seen that I provide in accordance with the present invention a very simple but effective and durable vise. The work may 20 be securely clamped in any desired position between the jaws 11 and 30 by merely inserting the work in the desired position between those jaws and then turning the screw 17 by means of the handle 18.

25 As many changes could be made in the above construction and many apparently widely different embodiments of this invention could be made without departing from the scope thereof, it is intended that all matter contained in the above description or 30 shown in the accompanying drawing shall be interpreted as illustrative and not in a limiting sense.

35 It is also to be understood that the language used in the following claims is intended to cover all of the generic and specific features of the invention herein described and all statements of the scope of the invention which, as a matter of language, might 40 be said to fall therebetween.

40 What I claim as my invention is:

45 1. In a vise of the character described, a channel-shaped slide, an angle bar located upon one end of and extending transversely of said slide and providing a vertical jaw face and a horizontally extending flange, a fixed transversely extending angle bar the vertical web of which last-mentioned angle bar constitutes a jaw opposed to said first mentioned 50 jaw, an L-shaped arm depending from the flange of said last mentioned bar and forming therewith a guide-way or groove in which said slide is mounted for reciprocating movement, a lug extending from said arm into said groove and into the channel of said slide, said lug provided with a threaded aperture, a screw journaled at its opposite ends in said slide and housed within the channel thereof, said screw extending through said threaded 55 aperture, and means carried by said L-shaped arm for clamping a support between itself and the horizontally extending flange of said fixed element.

60 2. In a vise of the character described, a slide channel-shaped in cross section and hav-

ing a slot in its inner wall, an angle bar formed integral with said slide and extending transversely thereof at one end to provide a vertical jaw and a horizontally disposed flange, a screw journaled in said slide 70 and housed within the channel thereof, a fixed angle bar forming a jaw opposed to said first mentioned jaw and a horizontally extending flange, an L-shaped arm depending from said last mentioned flange and forming therewith a guide-way or groove in which said slide is mounted for endwise movement, a lug carried by said arm extending into said channel and groove and providing a nut working on said screw, and a 80 clamping screw threaded in the end of said arm and opposed to said second mentioned flange.

3. In a vise of the character described, a movable jaw element having a bar adapted to extend along the edge of a support, and a jaw arising from and extending transversely of said bar and adapted to overhang the top surface of said support; and a fixed jaw element having a jaw opposed to said first 90 jaw and extending transversely of said bar, said fixed jaw element having an arm extending downwardly and then transversely of said bar and forming an open channel in which said bar is slidably mounted; a screw 95 carried by said movable jaw element; said fixed jaw element having a threaded aperture receiving said screw in threaded engagement; and means carried by said arm for clamping said vise to a support.

4. In a vise of the character described, a fixed jaw element having a jaw one end of which is adapted to engage against the top surface of a support, and an L-shaped arm having a depending portion and a horizontally extending portion parallel to the face of said jaw, the lower edge of said jaw, the inner face of said depending portion of the arm and the upper surface of the horizontally extending portion of the arm forming an open channel; a movable jaw element having a bar slidably engaging in said open channel and adapted to extend along the edge of a support, said movable jaw element having a jaw opposed to said fixed jaw and extending transversely of said bar; a screw carried by said bar; a lug on the depending portion of said arm and extending into said channel and receiving said screw; and clamping means on the inner end of the horizontally extending portion of said arm and between which and the lower edge of the fixed jaw the support is adapted to be clamped.

5. In a vise of the character described, a movable jaw element having a slide channel-shaped in cross section, and a jaw arising from said slide and extending transversely thereof; a screw journaled in said slide and extending longitudinally of the channel therein; a fixed jaw element having a jaw op-

posed to said first mentioned jaw and extending transversely of said slide, and an L-shaped arm depending from said jaw and having a horizontally disposed portion which is parallel to the face of the jaw of said fixed jaw element, said fixed jaw element having an open channel in which said slide is slidably mounted; a nut carried on the inner face of the depending portion of said L-shaped arm extending into said slide and working on said screw; and a screw clamp carried by the inner end of said horizontally extending portion of said arm.

CHRISTIAN BODMER.
